UNITED STATES PATENT OFFICE.

ABRAHAM D. HEDGES, OF LONG BEACH, CALIFORNIA.

SIGNALING DEVICE.

1,316,481.

Specification of Letters Patent. Patented Sept. 16, 1919.

Application filed January 21, 1919. Serial No. 272,272.

To all whom it may concern:

Be it known that I, ABRAHAM D. HEDGES, a citizen of the United States, residing at Long Beach, in the county of Los Angeles and State of California, have invented certain new and useful Improvements in Signaling Devices, of which the following is a specification.

This invention relates to signaling devices, and preferably to that type designed for signaling or alarming pedestrians or drivers of vehicles of the approach of a vehicle, and to this end, the signaling device may be arranged either at a street crossing or intersection, or the signaling device may be located at a distance remote from the crossing, intersection, highway or other place.

It is an object of the present invention to provide a simple, inexpensive, economical and durable device, which can be depended upon to actuate positively and quickly to give proper warning to a pedestrian and in such a way as to indicate by sound or otherwise the approximate speed at which the oncoming vehicle is approaching.

Another object of the invention resides in the provision of a signaling device embodying among other characteristics, a signal proper which is exceedingly sensitive, and so sensitive that the very slightest contact of a vehicle or object with the actuating device will effect a vibratory action of one of the elements of the signaling device in accordance with the actuation given it by the actuating device with the result that upon slight or slow movement of the actuating device, the warning given is not as vigorous as when sharp or quick contact is made with the actuating device, in which event the vibration of one part of the alarm is such as to give quick, snappy, or forceful actuations, indicating to the pedestrians and drivers that the on-coming vehicle is approaching with great speed, and thereby giving such an alarm to the pedestrian as to warn him to move quickly out of the roadway.

With these and other objects in view, the invention consists in the construction and novel combination of parts hereinafter fully described and illustrated in the accompanying drawings and pointed out in the claims hereto appended, it being understood that various changes in the form, proportion, size and minor details of construction,

within the scope of the appended claims, may be resorted to without departing from the spirit or sacrificing any of the advantages of the invention.

60

In the drawings:

Figure 1 is a diagrammatic view in perspective, illustrating one embodiment of my invention.

Fig. 2 is a cross sectional view through a roadway or street crossing, illustrating this particular embodiment of the invention.

Fig. 3 is a detail fragmentary perspective view illustrating a connection between the signaling device proper and the actuating device therein.

Fig. 4 is an enlarged detail sectional view of the upper end of the signaling device.

Fig. 5 is a cross sectional view through a roadway illustrating a very important embodiment of my invention.

Fig. 6 is a fragmentary perspective view, partly in full lines and partly in dotted lines, illustrating the connection between the actuating device and the vibrating element of the signal illustrated in Fig. 5.

Referring now to the accompanying drawings, and more particularly to Figs. 1 to 4, inclusive, which embodies one form of my invention, but which is not particularly the preferred form, which I might adopt, there is illustrated an intersection or street crossing 1, at each corner of which is located a hollow column 2 provided at its upper end with a supporting device 3 designed to rigidly or pivotally support a bell 4 which is adapted, in this particular embodiment of the invention, to ring under the influence of suitable actuating devices, to sound effectively an alarm to a pedestrian or the driver of the approach of a vehicle.

In the particular embodiment of the invention now being described, the actuating device for each bell is located at a distance remote from the crossing, say for purposes of illustration, one hundred feet, more or less. This actuating device preferably extends half way across the road-way and is located in a suitable trough 5 which at one end extends preferably under the pavement, as shown at Fig. 2, for a purpose presently explained.

The actuating device consists of two arms 6 and 7 which are preferably connected together by a resilient metallic or other suitable resilient member 8. The outer end of the member 6 of the actuating device is piv-

105

110

oted in the trough 5 at 9. The outer end of the member 7 of the actuating devices is screwed or otherwise fitted fixedly in a socket 10 of a T-shaped coupling 11 located under 5 the pavement, as illustrated in Fig. 2.

In each column 2 is a relatively short rigid arm 12. The lower end of this arm 12 is fixedly secured in a T-shaped coupling 13. This arm 12 located in each of the 10 columns is connected with the respective actuating device by a rock shaft 14 located in a suitable housing 15. This rock arm is journaled in the lower embedded end of the respective column as indicated at 16 15 and is fixed adjacent its ends in the aforesaid T-couplings 11 and 13, the end of the rock arm 14 adjacent the actuating device being journaled at 17 in the aforesaid trough 5 as is clearly shown particularly in 20 Fig. 3.

An exceedingly thin and resilient clapper arm 18 of relatively long length is secured to the upper end of each of the aforesaid arms 12 located in the columns 2. These 25 clapper arms 18 are of relatively long length and thin so as to render them exceedingly resilient to provide for great vibration under the influence of slightest action given thereto as the result of contact of a vehicle 30 or object with the respective actuating devices 6—7—8. The vibration of the clapper arms 15 have the function, incident to their extreme sensitiveness, of vibrating slowly or rapidly under the influence of the actuating device, as will now be understood, and if a vehicle is moving slowly over the street or 35 road-way and contacts with the respective actuating device, the vibration of the respective clapper arm against the respective bell 40 4 will give an alarm to the pedestrian at the crossing. If the sound is rather light, the pedestrian will know, as the result of city or town ordinances or warnings that the vehicle is approaching slowly. If the vehicle 45 contacts sharply with the actuating device, which it will do under great speed, the greater will be the vibratory action of the clapper arm, and consequently more vigorous will be the sound or warning to the pedestrian, indicating to the pedestrian that the vehicle is approaching with more or less 50 great speed. Thus, the sensitiveness of the structure involved here is such that the sound or warning will be made in sound according 55 to the actuation of the signaling devices under the influence of the actuating devices according to the sharp or gradual depression of the element 6—7—8 of the actuating devices as will now be understood.

60 The actuating arms 6 and 7 and the connection 8 extend preferably very slightly above the upper edges of the trough 5 so that upon contact therewith of the wheels of a vehicle they may be depressed to operate 65 the respective rock shaft 14 and thereby ac-

tuate the vibratory devices constituted by the arms 12 and 18. The arms 6 and 7, as also the arms 12 and 14 may be composed of hollow tubing, but if preferred, the actuating arms 6 and 7 may be of another form, 70 but their upper edges, in any event, are preferably rounded so as to prevent injury or undue wear to rubber tires of motor vehicles.

In another embodiment of my invention, 75 which will be preferable in many instances, I dispense with the rock shaft 14 and by reference to Figs. 5 and 6, I mount the column 2' directly opposite the actuating devices A, the same in construction as the aforesaid actuating devices, and I connect the arm 7' of the actuating devices directly to the vibratory arm 12—18 by a bell crank lever 19 so that upon actuation of the actuating device in this second form of the invention 80 there is a direct action on the vibrating arm and the pedestrian is warned by the sound of the alarm at a distance from the crossing, say, for the purpose of illustration, one hundred feet, more or less. 85

It will thus be seen that both forms of the invention are substantially the same. The only difference is that in the first form described the signaling device is located directly at the crossing and the actuating device at a distance therefrom, necessitating the use of a rock shaft such as that illustrated at 14. In the second form of the invention, the rock shaft 14 is dispensed with and both the actuating devices and the signaling devices are arranged at a distance away from the crossing, but the alarm given is such that it will be heard by the pedestrian at the crossing and the functions due to the sensitiveness of the signaling devices 90 hereinbefore described will be performed and heard and recognized and understood by the pedestrian at the crossing under the operation of the device described in this second form the same as in the case of the form of 95 the invention first described. The difference is slight. The principles are the same in both cases and the characteristics of both devices are all common to both. Hence the claims herein presented are drawn to cover 100 broadly both forms of the invention with one set of claims presented specifically to 110 one form of the invention.

115 It will be understood that my invention is applicable not only to street crossings and 120 intersections, but it is equally applicable for use in highways, between crossings and intersections and particularly in close proximity to dangerous curves and turns on highways.

125 What is claimed is:—

1. In a signaling device, a hollow vertical column embedded at its lower end in the ground alongside of the roadway, a bell supported at the upper end of the column, an 130

- actuating device located in the roadway for contact with and actuation by a vehicle, a rock-shaft having one end journaled in the embedded end of said hollow column and extending into the latter, an arm rigidly connected to the rock-shaft and extending upwardly into the column, a flexible vibratory clapper-arm secured to the aforesaid arm to coact with said bell, and a coupling connection between the actuating device and the rock-shaft whereby upon actuation of the actuating device the shaft is rocked and the flexible clapper-arm vibrated to ring said bell.
- 15 2. In a signaling device, signaling means located alongside of the roadway, and an actuating device arranged in the roadway for contact with and actuation by a vehicle, said actuating device consisting of two alining arms and a resilient connection between the inner ends of said arms, one of said arms having operative connection with said signaling means to operate the latter upon actuation of the actuating device.
3. In a signaling device, signaling means located alongside of the roadway, and an actuating device arranged in the roadway at a point remote from the signaling means for contact with and actuation by a vehicle, said device consisting of two alining arms, one of the arms being pivoted at its outer end, a connection between the inner ends of said arms whereby said pivoted arm is maintained in alinement with its alining arm, and a connection between the innermost of said arms and the signaling means to operate the latter upon actuation of the actuating device.

In testimony whereof I affix my signature.
ABRAHAM D. HEDGES.
